UNITED STATES PATENT OFFICE.

LEWIS HALLOCK NASH, OF SOUTH NORWALK, CONNECTICUT, ASSIGNOR
TO NATIONAL METER COMPANY, OF NEW YORK, N. Y., A CORPOR-
ATION OF NEW YORK.

WATER-METER-CONTROLLING DEVICE.

No. 832,619.

Specification of Letters Patent.

Patented Oct. 9, 1906.

Application filed October 24, 1903. Serial No. 178,313.

To all whom it may concern:

Be it known that I, LEWIS HALLOCK NASH, a citizen of the United States, and a resident of South Norwalk, in the county of Fairfield 5 and State of Connecticut, have invented a new and Improved Water-Meter-Controlling Device, of which the following is a full, clear, and exact description.

My invention relates to improvements in 10 water-meters, and comprises certain novel features, which will be particularly pointed out in the claims.

The following is a description of the devices shown in the accompanying drawings, 15 which illustrate forms in which I at present prefer to embody my invention; but it will be understood that various changes and modifications may be made without departing from the spirit of my invention and without 20 exceeding the scope of the concluding claims.

In the accompanying drawings, Figure 1 is 25 a sectional view of a meter embodying a controlling device involving my invention, showing it in its normal position. Fig. 2 shows the same controlling device closed. Fig. 3 is 30 a top view of that portion of the case in which said controlling device is located. Fig. 4 is another form of controlling device involving my invention, the valve being in the open position. Fig. 5 shows the device of Fig. 4 with the valve partially closed. Fig. 6 shows 35 another form of controlling device involving my invention, this form possessing the additional function of acting as a check-valve. Fig. 7 is another form involving my invention, 40 acting both as a reducing-valve and a check-valve. Fig. 8 shows a main with a meter attached and a controlling device—such, for example, as one of those herein described—located between the main and the meter.

Water-meters are commonly located in 45 places where the pressure of the water varies within relatively wide limits—say, for example, from thirty to one hundred and fifty pounds per square inch. If a meter be provided with a passage sufficiently ample to permit it to work at its full capacity under, say, fifty pounds pressure, then that meter 50 will be endangered by the increased flow due to any considerable rise of pressure above

fifty pounds. The common practice is to avoid this danger by throttling the passage through the meter at some point, so that it will not be overworked at any expected abnormal pressure; but the disadvantage of this expedient is that at normal pressures the flow is unduly restricted, either necessitating the installation of a meter larger than necessary or curtailing the amount of water available for use. By my invention, among other things, I overcome this difficulty and am enabled to use without danger to it a meter which under normal conditions may be worked at substantially its maximum capacity. 55

In the drawings, 1 is a passage leading from the water-main.

2 is a passage connecting the passage 1 with the chamber 3, which contains the meter mechanism. 70

4 is the registering mechanism.

5 is the meter proper, and 6 is the outlet-passage from the meter. It is deemed unnecessary to describe the meter, which is 75 shown in detail, as it is of a type well known on the market as the "Crown." It is to be understood, however, that I do not limit the application of my device to this type of meter, as it may be applied as well to any other 80 type.

Referring now to Figs. 1, 2, and 3, in the passage 2 is located the device for controlling the flow of water through the meter. This device is here shown as made in the form of a 85 hollow cylinder 7, the inside walls of which are inclined so as to present a resistance to the current-flow. The device is held in place by means of the pin 8. On the case above the cylinder 7 is formed the projection or 90 seat 9.

The operation of the device is as follows: Water flows from the main through the hollow cylinder 7 and through the meter, wherein it will be measured, passing out through 95 the passage 6. When the pressure of the water rises above the normal, the water will cause the cylinder to rise, thereby reducing the opening between the top of the cylinder and the seat 9, thus diminishing the flow into 100 the chamber 3. If the pressure becomes so great as to cause the cylinder to rise until it

comes in contact with the seat 9, flow of water would be entirely cut off, and the cylinder would then fall to a position of equilibrium, where the energy expended by the flow through the cylinder equals the weight of the cylinder substantially. Thus the largest possible discharge is allowed up to the limit of the proper capacity of the meter, and any increase of flow above the capacity of the meter is prevented. The advantage of such a device is apparent especially for fire-service meters, as in its normal and proper use it causes the least possible resistance to the flow of the fluid, and therefore the least possible loss of head.

In the modification shown in Figs. 3 and 5 the passage 1 communicates with the passage 2 by means of an opening 10, formed in a partition which separates the two passages. Through this opening extends the spool-shaped device 11, its lower end resting within a pocket 12, formed in the case. This device is held in place by means of a pin or bolt 13, which passes through the center of the device and which is screwed into the case. The pin or bolt is provided with a head 14 and is longer than the device 11. When the water is at normal pressure, the device will be in the position shown in Fig. 4, and the water will readily pass through the opening 10 and around the head of the device into the passage 2 and thence to the meter. Should the flow increase above a given amount, the water bearing upon the head of the device will cause it to rise on the bolt or pin 13 until it strikes the head 14, thus diminishing the size of the inlet-passage, as shown in Fig. 5. In this modification there is always some opening for the water to enter the meter. In Fig. 6 the head of the device 11 is formed to fit snugly in the opening in the partition separating the two passages 1 and 2. In the operation of this form of device the water at normal pressure will cause the device to rise sufficiently to allow the water to flow through. At an increased rate of flow the pressure will cause the device to rise further, as described in reference to Figs. 4 and 5, until it strikes the head 14 of the pin 13 and throttles the flow. In this modification the device constitutes not only a reducing valve, but also a check-valve, preventing any backflow or reversal of flow through the meter and prevents the meter being run backward by reversing its position on the service-pipe.

In the modification shown in Fig. 7 in the passage 2 is pivoted at 15 a swinging device or valve adapted to close the opening 17 when at rest and to throttle the flow into the meter when it has been elevated to a certain extent. The operation of this form is as follows: The water under normal pressure will pass from passage 1 through opening 17,

causing the valve 16 to rise sufficiently to 65 permit the water to flow. Thence the water will pass from passage 2 through opening 18 and passage 2^a to chamber 3. When the flow of the water increases above normal, the valve 16 will be forced upward until the energy expended by the flowing stream on the valve equals the weight of the valve, which will be substantially the position of equilibrium.

The controlling valve or device may be located in the meter-case, as I have shown it in Figs. 1 to 7, or it may be located, as shown in Fig. 8, at C, between the main A and the meter B.

In the foregoing specification I have described certain modifications of structures involving my invention; but it will be understood that various other modifications and forms may be adopted and that mention by me of a few modifications is not intended to exclude others not referred to, the object of this specification being to instruct a person skilled in the art how to practice my invention in forms which are at present preferred by me. All of the details and features illustrated and described are not essential to the practice of my invention broadly considered. This will be indicated in the concluding claims, where the omission of an element or feature hereinbefore described is intended to be a specific declaration that the omitted element or feature is not essential to the invention therein covered.

What I claim, and desire to secure by Letters Patent, is—

1. The combination with a water-meter of a valve constructed and arranged to remain wide open while the rate of flow is confined within substantially normal limits and to partially close and throttle the flow through the meter when the rate of flow exceeds the normal.

2. The combination with a water-meter of a valve constructed and arranged to remain wide open while the rate of flow is confined within substantially normal limits and to progressively close and progressively throttle the flow through the meter when the rate of flow exceeds the normal.

3. The combination with a water-meter of a non-closing valve constructed and arranged to remain wide open while the rate of flow is confined within substantially normal limits and to partially close and throttle the flow through the meter when the rate of flow exceeds the normal.

4. The combination with a water-meter of a non-closing valve constructed and arranged to partially close and throttle the flow through the meter when the rate of flow increases.

5. The combination with a water-meter of a pressure-balanced valve constructed and arranged to partially close and throttle the

flow through the meter when the rate of flow increases.

6. The combination with a water-meter of a valve constructed and arranged to partially close and throttle the flow through the meter when the rate of flow increases and to close when the direction of the flow is reversed.

In testimony whereof I have signed my name in the presence of two subscribing witnesses.

LEWIS HALLOCK NASH.
